United States Patent Office.

RICHARD H. CHINN, OF WASHINGTON, DISTRICT OF COLUMBIA.

Letters Patent No. 66,675, dated July 16, 1867.

IMPROVED NUTMEG-GRATER.

The Schedule referred to in these Letters Patent and making part of the same.

TO ALL WHOM IT MAY CONCERN:

Be it known that I, RICHARD H. CHINN, of the city and county of Washington, and District of Columbia, have invented a new and useful improvement in Nutmeg-Graters; and I do hereby declare the following to be a full, clear, and exact description of the same, reference being had to the accompanying drawings, forming part of this specification, and in which—

Figure 1 is a perspective view of my invention.

Figure 2 is a perspective view of the nutmeg-holder, showing its internal construction.

Similar letters of reference indicate corresponding parts in the two figures.

In this invention the nutmeg is held in a sliding-box working over the grater, against which it is pushed by a spring in the sliding-box.

The object of the invention is to enable the operator to use up the entire nutmeg without bringing his fingers into contact with the rough face of the grater, and thereby wounding them.

In the drawings, A represents a tin box having one of its sides punched with small holes, so as to form a grating-surface, B, on the inside of the box. The opposite side of the box is open, its edges α being turned in slightly their whole length, and a flange or lip, α' , being attached to the sides of the box over the edges α from the point c to c' , about four-fifths the length of the box A, so as to form between the flanges α' and the edges α grooves, in which the sliding-box is guided, so that it shall always run in a plane parallel to the grating-surface B. C is a conducting-tube on the box outside of the grating-surface, catching the grated nutmeg and delivering it from the ends of the tube C. i is an aperture opening from the interior of the box A into the lower end of the conducting-tube C, through which all the grated nutmeg that does not pass through the perforations in the plate B escapes into the conducting-tube. E is the sliding-box, which holds the nutmeg while the operation of grating is performing. The body of it is oblong, and has a spiral spring, F, in its centre, pressing against the nutmeg, and holding it down against the grating-surface. Above the top of this oblong box is a rectangular collar, e, and projecting above that a handle, E'. The body of the box is too long to go through between the bent edges α , except sideways. When it has been thus inserted at the end of the flanges α' , turn it a quarter round, so that the body of the box E shall run under the bent edges α , while the collar e slides in the groove between the edges α and the flanges α' . H is a hook by means of which to hang the grater up when not in use.

The nutmeg is placed in the sliding-box E upon the spring F, and the box E is then inserted into the box A as above described. By sliding the box E backward and forward in that position, by means of the handle E', the operation of grating is effectually performed.

The handle E' may be made a hollow cylinder, having the shaft or piston K sliding vertically in it, so that the piston K can be pressed down upon the nutmeg by pressure upon the head or thumb-piece L, and the nutmeg then be held against the grating-surface by the action of the operating thumb. When this form is used the spiral spring F may be omitted.

Having thus described my invention, what I claim as new, and desire to secure by Letters Patent, is—

The box A, having a foraminous bottom, B, and below it a conducting-tube, C, in combination with the nutmeg-holders E fitted to slide within the box A, handle E', and sliding piston K L, when arranged to operate in the manner and for the purpose specified.

To the above specification of my improvement I have signed my hand this 18th day of May, 1867.

RICH'D H. CHINN.
